COMBINATION LOCK

Ernest Kertland Smith, Toronto,
Ontario, Canada

Application April 2, 1947, Serial No. 738,899

4 Claims. (Cl. 70—305)

1

This invention relates to a combination lock of the general class which have a plurality of rotatably mounted discs notched to receive a locking bar whereby to cause the lock to open.

Combination locks have been provided in the past. With them, however, it has been necessary to rotate pointers to predetermined positions on dials or otherwise position them in predetermined positions. These locks cannot be operated in the dark, or by a blind person. It is possible to operate the lock of my invention in the dark.

It is, therefore, an object of this invention to provide a combination lock which can be operated in the dark.

It is a further object of the invention to provide a combination lock which is cheap to manufacture.

It is a further object of the invention to provide a simple combination lock in which the combination can be readily altered.

Accordingly, the invention generally comprises a lock having a plurality of notched locking discs designed to receive a locking bar. Means are provided for causing each of the discs to rotate to a reference position and means are provided for independently actuating each of the discs so that its notch aligns with the locking bar. When all of the notches are in alignment with the bar, the bar will drop into them to unlock the lock. The means for actuating the discs preferably includes a lever adapted to repeatedly engage with the disc whereby to rotate it a predetermined amount on each engagement.

The invention will be clearly understood after reference to the following detailed specification taken in conjunction with the drawings.

In the drawings:

Fig. 1 is a rear view of the lock showing the mechanism.

Fig. 2 is a section through the lock along the lines 2—2 of Fig. 1.

Fig. 3 is a perspective view of a release for the locking disks.

Fig. 4 is an enlarged view of a preferred form of locking disc.

Fig. 5 is a cut away view of a door or the like showing the manner of mounting the actuating plate.

Fig. 6 shows an actuating plate.

Fig. 7 is a front view of the lock.

Fig. 8 is a detailed view of the disc release means.

As mentioned above this invention relates to a combination lock of the class having a plurality of locking discs, notched to receive a locking bar whereby to cause the lock to unlock. The drawings, therefore, show four discs 10, notched as at 11, and rotatably mounted on a shaft 12 carried by the frame 13. A locking bar 14 extends across the four discs 10 and is designed to enter into the notches 11 of the discs 10 when they are all

2

aligned therewith. The manner in which the bar causes the lock to unlock when it enters the notches 11 is well known in the art and is not shown in the drawings.

My invention resides in the novel and improved method for causing the discs to rotate whereby to align the notches with the locking bar. With this construction I am able to obtain all the objects of my invention. Accordingly, means are provided for causing each of the discs to rotate to a predetermined position. These means include a ratchet wheel 15 carried by each disc and a spring 16 secured to the shaft 12 and the ratchet wheel 15, designed to urge the disc in a counterclockwise direction to cause the stop pin 17 to engage with the stop 18 on the frame 13 of the lock.

A locking finger 19, however, normally engages with the ratchet 15 as shown in Figure 1 to prevent the above described action. The locking fingers 19 are all mounted on a bar 20 which is suitably journaled in the lock frame as at 21 and projects therefrom as at 23. Disc release means comprise a turning knob 24 which is fixed to the projecting end, each finger 19 having an opposed arm portion 19a carrying a pivotally connected link 19b which extends to engage pins 14a of bar 14 by the elongated slot 19c at its upper end (see Figure 8). When it is desired to cause the discs to rotate to their reference position it is merely necessary to turn the knob 24 in a counterclockwise position against the spring 26. This causes the fingers 19 to disengage from the ratchets 15 and bar 14 to disengage from slots 11 of discs 10 and permits the spring 16 to rotate each of the discs until the stop pins 17 engage the stops 18. As soon as the knob 24 is released, the fingers 19 will again engage the ratchet 15 to hold the discs against counterclockwise movement.

The means for actuating the discs from the reference position includes a lever 27 rotatably mounted on a shaft 28 which is suitably mounted in the frame, and a pawl 29. The pawl 29 is pivotally carried by the lever as at 30, and a spring 31 urges it into engagement with the lever as shown at 32. A spring 33 secured to the frame as at 34 and the lever as at 35, causes the lever to assume a normal position against the stop bar 33a so that the pawl 29 is out of contact with the ratchet 15.

It will be understood that one lever only has been described. There is, however, a separate lever for each disc as indicated in the drawings.

Each of the levers 27 is adapted to be actuated from its normal position by an actuating pin 36. When the lever is actuated it rotates on the shaft 28 to cause the pawl 29 to engage with a tooth on the ratchet wheel 15 and actuate it a predetermined amount.

The second lever from the back as seen in Figure 1 is shown in an actuated position. As the

pawl engages with the ratchet it rotates it a predetermined amount and then turns in its mounting 30 against the pressure of the spring 31 to cause the pawl to disengage from the lever as indicated at 38 in Figure 1. Thus, further actuation of the lever will not actuate the ratchet more than the predetermined amount. As soon as the actuating lever is returned to its original position the spring 33 draws the lever back to its normal position and the spring 31 causes the pawl 29 to assume its normal position. Thus, each time that a pin 36 is actuated its corresponding disc moves a predetermined increment.

In the embodiment of the invention shown, the actuating surfaces of the four levers are designed to lie in a cross-like configuration as seen from Figure 1 and the actuating pins 36 are all mounted on a plate 39. The plate 39 is slidably mounted within the guide channels 40 formed in a door 41 or the like, in which the lock is mounted. A cover plate 42 secured to the door 41 by rivets as at 43 has guide grooves 44 formed therein to permit the projection of an actuating knob 45. By actuating the knob 45 within the guide grooves 44 the pins 36 are caused to actuate the levers.

The pins 36 are mounted in spaced apart relation on the plate 39 to normally take up the dotted line positions shown in Figure 1. When they are in this position they each contact a separate arm 27 in its normal position. To actuate the lock the plate 39 is actuated within its guides 40 by moving the knob 45 from its normal position at the centre of the cross-like configurations formed by the guide grooves 44. Thus, when the knob is moved in the guide groove 44a the pins 36 will all move from the dotted line positions to the solid line positions shown in Fig. 1. It will be noted that only one of them operatively engages a lever to cause its respective disc to rotate one notch of its ratchet wheel (shown by the dotted lines of Fig. 1). Similarly, when the knob 45 is actuated in any of the other three grooves it will operatively engage one of the other levers to move that respective disc a predetermined distance. It will be apparent that the disks 10 can be rotated to a predetermined position such that a known number of actuations will cause the notches 11 to align with the locking bar 14 to unlock the lock by moving the knob 45 within the grooves 44.

In Fig. 4 I show a preferred type of locking disk. It comprises a disk 10a notched as at 11a in a somewhat similar manner to the disk 10. This disk, however, is not stamped in one piece as is the disk 10. It is made from a thicker piece of metal and has a plurality of radially extending holes 46 in its circumference each adapted to receive a stop peg 17a. With this disk if it is desired to change the lock combination it is merely necessary to move the pin 17a from one hole to another so that it will require a different number of actuations of the lever to move the disk from the reference position in which the pin is in contact with the stop 18.

From the above, it will be apparent that I have disclosed a combination lock which can be operated in the dark or by a blind person. The principal component parts of the lock can all be stamped thus providing a lock which is cheap to manufacture. The lock is very rugged and it can be made in a form in which it is possible to vary the combination with a minimum of trouble. Changes and modifications in the form of the invention shown will be apparent to those skilled in the art and it is therefore not intended that

my invention should be limited to the specific form shown.

What I claim as my invention is:

1. In a combination lock having a plurality of pivotally mounted notched discs, a locking bar designed to fall into the notches of the discs when aligned for an unlocking position, a ratchet means for each disc, actuating means for causing incremental rotation of said discs when the notches thereof are not engaged by said locking bar, said actuating means comprising a lever arm mounted adjacent each disc, means extending from each lever designed to engage the ratchet means of its adjacent disc to provide incremental rotation of said disc upon swinging movement of said lever, an actuating member having means extending therefrom for selective engagement with said levers whereby an operator gripping said member may cause selective actuation of said discs by moving said member in a selective direction transversely of the pivotal axis of each of said levers, certain of said levers being actuatable by movement of said actuating member in a different selected direction than the direction of movement of said member employed for actuation of certain other of said levers.

2. In a combination lock the combination claimed in claim 1 and a guide means determining the bounds of selective movement of said actuating member.

3. In a combination lock the combination claimed in claim 1 and a guide means determining the bounds of selective movement of said actuating member said bounds being a crosslike configuration.

4. In a combination lock having a housing, a plurality of notched pivotally mounted discs, a locking bar designed to fall into the notches of said discs when said notches are aligned corresponding to an unlocking position and a ratchet means for each disc; actuating means for causing incremental rotation of said discs when the notches thereof are not engaged by said locking bar comprising; a pivotally mounted lever mounted adjacent each disc, a pawl extending from one free end of each lever designed to engage the ratchet means of its adjacent disc upon positive swinging movement of the corresponding lever, an actuating member slidably mounted relatively to said housing and moveable in a plane transverse to the axis of each lever, means extending from said actuating member for selective engagement with each lever, spring means in connection with said levers for biasing the same toward the means extending from said actuating member, said actuating member being moveable to cause swinging movement of a selected lever by engagement of the means extending from said actuating member with said selected lever and to provide incremental rotation of its adjacent disc by engagement of its associated pawl with its associated ratchet means.
